UNITED STATES PATENT OFFICE.

RICHARD RADDATZ, OF MILWAUKEE, WISCONSIN, ASSIGNOR TO WHIRLPOOL MIXER & MACHINERY COMPANY, OF MILWAUKEE, WISCONSIN, A CORPORATION OF WISCONSIN.

MIXING-MACHINE.

1,232,605.

Specification of Letters Patent. Patented July 10, 1917.

Application filed March 12, 1909. Serial No. 482,946.

To all whom it may concern:

Be it known that I, RICHARD RADDATZ, a citizen of the United States, residing at Milwaukee, in the county of Milwaukee and State of Wisconsin, have invented certain new and useful Improvements in Mixing-Machines, of which the following is a specification, reference being had to the accompanying drawing, forming a part thereof.

10 This invention relates to machines for mixing the constituents of concrete and the like.

The main objects of this invention are to render the entire length of the drum and flights effective and thus increase the capacity or output of a machine of given dimensions; to provide for mounting and operating the drum close to the surface on which the machine stands, thereby avoiding elevation of the material for charging the drum; to facilitate discharging material from the drum; and generally to simplify and improve the construction and operation of machines of this class.

25 It consists in the construction, arrangement and combinations of parts as herein-after particularly described and defined in the claims.

In the accompanying drawing like characters designate the same parts in the several figures.

Figure 1 is a side elevation of a machine embodying the invention, a method of direct low charging being illustrated; Fig. 2 is an enlarged vertical longitudinal section of the same showing the reversible chute in position to receive material from the ascending flights and deliver it back into the lower part of the drum toward the charging end thereof; Fig. 3 is a vertical cross section on the line 3-3, Fig. 2; and Fig. 4 is a section similar to that of Fig. 2 but showing a modification of the flights and the reversible chute in discharging position.

45 The machine comprises a truncated cone or frustum-shaped drum *a*, mounted with its axis inclined downwardly toward its smaller end in a frame *b* close to the ground, floor or surface upon which the frame rests.

50 The drum is provided with internal longitudinal flights *c*, which may be attached to and rotate therewith, or may be independently supported and rotatable, while the drum is stationarily mounted on the frame.

In the present case the drum is shown as rotatably mounted upon the frame and the flights *c* are attached thereto. It may be conveniently constructed as shown in Fig. 2, of a sheet metal or boiler plate shell riveted at the ends to flanged heads *d* and *e* of cast iron, the heads being annular or formed with central openings for charging and discharging the machine.

The drum may be rotatably carried as shown in Fig. 1, on rollers *f*, which are mounted on the frame *b* and work with circular treads or ways *g* formed on the drum heads *d* and *e*. The drum with its flights *c* is turned in the direction indicated by arrows on the drawing, by a bevel pinion *h*, meshing with a circular rack or gear *i* on the head *e* and fixed on a horizontal shaft *j* which is mounted at right angles to the axis of the drum in a stand on the frame *b*. The drum is preferably hung or mounted in the frame *b* as shown, so that its lower side is inclined downwardly toward its larger or charging end, while the axis about which the drum rotates, inclines downwardly in the opposite direction toward its smaller or discharging end.

A deflector or chute *k* is carried by links *l* and *m* connecting it with a bracket on the rear sill of the frame *b* in such a way that it may be shifted from its working or mixing position in which it is shown in Fig. 2, to its discharging position in which it is shown in Fig. 4, or vice versa, its inclination being reversed in changing it from one position to the other.

A lever *n* fixed on the shaft or extended pivot pin *o* on which the links *m* are mounted at their lower ends, affords means for rocking said links and shifting the chute *k* from one position to the other.

The flights *c* are curved upwardly on the ascending side of the drum at their ends adjacent to the head *e* and terminate a short distance from said head, as shown in Fig. 2, to concentrate the discharge of material therefrom into the chute *k* and to operate more effectively in mixing the material. In place however, of the curved flights, the machine may be provided with straight flights *c'* extending completely to the head *e*, as shown in Fig. 4.

For mixing certain materials, particularly those of a sloppy nature, the drum is pro-

- vided adjacent to the opening in the front end with an internal shield *p*, which may be of circular shape and fastened to the drum so as to turn with it, as shown in Fig. 2, or supported independently thereof by arms or braces passing from the frame through the charging opening, as shown in Fig. 4, in position to prevent the splashing of the material through said opening.
- 10 This shield is located within the drum at a distance from the charging opening to admit of the introduction of material into the drum through said opening without changing the position of the shield.
- 15 To facilitate the transportation of the machine from place to place, the frame *b* may be provided with removable or folding truck wheels, which are not shown.
- The machine may be charged as shown in Fig. 1, by dumping the material into the drum through the opening in its larger end from wheelbarrows *q* run up on a gradually inclined plank *r*, resting on the front sill of the frame *b*, or the material to be mixed may 25 be shoveled directly into the drum. In this way the labor and time required to elevate the material to a higher level according to common practice, are saved.
- In the operation of the machine the drum 30 or flights being rotated in the direction indicated by arrows, and the chute *k* being set in the position shown in Fig. 2, the material deposited in the lower part of the drum adjacent to the head *d* is taken up by the ascending flights. The inclination of the flights during their ascent being reversed as the result of the conical or frustum shape of the drum, and the inclination of its axis, the material thus elevated gradually slides down toward 35 the rear end of the machine and is distributed along and discharged from the inner edges of the flights, a part of it falling into the reversely inclined chute *k*, by which it is conveyed back toward the front of the machine into the lower part of the drum 40 for further treatment, as explained. A part of the material elevated by the flights, falls therefrom directly back into the lower part of the drum to be again taken up by the succeeding flights, the course of the material 45 during the operation of mixing a batch being approximately indicated by arrows in Figs. 2 and 3. In this manner the entire length of the drum and flights is brought 50 into effective action in mixing the material of the charge or batch, which is passed to and fro from one end of the drum to the other, elevated, turned upon itself and thoroughly and expeditiously mixed. After it 55 has been thoroughly mixed the material is discharged while the drum or mixing mechanism continues to rotate, through the opening in the rear head, by tilting the chute *k* into the position in which it is shown in 60 Fig. 4, in which position it receives the mate-

rial as it is discharged from the lower portions of the ascending flights and conveys it through said opening.

Various changes in details of construction and arrangement of parts may be made without departing from the principle and scope of the invention.

I claim:

1. In a mixing machine, the combination of a frame, a revoluble frustum-shaped drum mounted thereon with its axis inclined downwardly with respect to the horizontal, and the bottom of the drum inclined downwardly in the opposite direction, the axis at the smaller end of the drum being lower than the axis at the larger end of the drum, heads provided with substantially central charging and discharging openings, respectively, partially closing the ends of the drum, elevating flights on the interior of the drum extending lengthwise thereof and projecting in a generally radial direction toward the axis of the drum to elevate material and move it toward the smaller end of the drum, and means to receive material elevated by the flights and return it toward the larger end of the drum.

2. In a mixing machine, the combination of a frame, a revoluble frustum-shaped drum mounted thereon with its axis inclined downwardly toward its smaller end and its lower side inclined downwardly toward its larger end, heads, provided with substantially central charging and discharging openings, respectively, partially closing the ends of the drum, and elevating flights on the interior of the drum extending lengthwise thereof, and projecting in a generally radial direction toward the axis of the drum to elevate material and move it toward the smaller end of the drum.

3. In a mixing machine the combination of a frame, rotatable, mixing means mounted thereon adapted to receive and retain the material being mixed and by its rotation to move said material in one direction, and a non-rotatable member arranged to receive the material and pass it back in the opposite direction for further movement reversely by the rotatable mixing means.

4. In a mixing machine the combination of a frame, a revoluble frustum-shaped drum mounted thereon with its axis inclined downwardly toward its smaller and discharging end, the inclination of said axis being such that the lower part of the drum is inclined downwardly in the opposite direction, said drum being provided on its interior with longitudinal flights and an inclined chute adapted to discharge material, dropped into it from flights, on to the lower part of the drum which is inclined downwardly away from the discharge end of the drum.

5. In a mixing machine the combination

- of a frame, a frustum-shaped drum rotatably mounted on said frame with its axis inclined downwardly with respect to the horizontal, the axis at the smaller or discharge end of the drum being lower than the axis at the larger or charging end of the drum, but the inclination of the axis with respect to the horizontal being such that the lower part of the drum is inclined in the 5 opposite direction with respect to the horizontal, and a chute downwardly inclined toward the larger end of the drum, adapted to receive material from ascending flights and return it toward the charging or larger 10 end of the drum and on the inclined bottom of the drum, and means for rotating said drum.
6. In a mixing machine the combination of a rotatable drum provided on the interior thereof with elevating flights which are all downwardly inclined on the ascending side of the drum toward the discharge end thereof, a chute, means exterior of the drum for supporting said chute, and means for 15 projecting said chute longitudinally into said drum and inclining it so that material received thereon will be returned toward the opposite end of the drum or withdrawing and reversing the inclination of said 20 chute so that material received thereon will be discharged outside the drum.
7. In a mixing machine the combination of a frame, a frustum-shaped drum rotatably mounted thereon with its axis inclined with respect to the horizontal, the axis at the smaller end of the drum being lower than the axis at the larger end of the 25 drum, but the inclination of the axis with respect to the horizontal being such that the lower part of the drum is inclined with respect to the horizontal in the opposite direction, said drum being provided with internal longitudinal flights and heads partially closing the ends thereof but leaving 30 substantially central charging and discharging 35 openings, a chute, a support for said chute located outside of said drum, and means for projecting said chute into said drum through the discharge opening in the 40 smaller end thereof, so that said chute may be inclined in said drum in the same direction as the bottom of the drum is inclined, so as to deliver material dropped into said 45 chute from the flights on to the inclined bottom of the drum and in the direction of its 50 inclination, and for withdrawing said chute from said drum so that said chute may be inclined so as to discharge material outside of said drum.
- 60 8. In a mixing machine the combination of a frame, a drum rotatably mounted thereon, and provided with elevating flights therein, to elevate material into a chute, a chute, a support for said chute located outside of said drum, a link pivoted both to 65 said support and to said chute for supporting said chute and a second link pivotally connected to said chute for swinging said chute and said first mentioned link and tipping said chute in oppositely inclined directions so that the chute can be swung into said drum and inclined so as to discharge material dropped into it into said drum and so that said chute can be swung outwardly with respect to said drum and inclined to 70 discharge material dropped into it outside of said drum.
9. In a mixing machine the combination of a rotary frustum-shaped drum having contracted openings in the ends and provided with internal longitudinal flights curved upwardly at the ends adjacent to and terminating at a distance from the smaller end of the drum, and means for rotating the drum, the axis of the drum being 75 inclined downwardly toward its smaller end.
10. In a mixing machine the combination of a frame, a frustum-shaped drum rotatably mounted thereon with its axis inclined downwardly toward its smaller end and having partially closed ends with substantially central charging and discharging openings, and internal longitudinal flights which are curved upwardly adjacent to the smaller end of the drum on the ascending side thereof, 80 means for rotating said drum, and a reversible chute, adapted in one position to deliver material received from ascending flights back into a lower part of the drum and in the other position to deliver such material 85 outside of the drum through the opening in its smaller end.
11. In a mixing machine the combination of a rotary drum provided with heads in which are substantially central charging and discharging openings, said drum being provided with flights on the interior 90 thereof to elevate material on the ascending side of the drum, means to discharge material elevated by said flights back into the lower part of the drum toward the charging end thereof, and a shield located within said drum between the charging opening and the means for discharging material back 95 into the lower part of the drum, said shield being spaced from the drum so that free communication exists between parts of the drum on opposite sides of said shield, said shield being at least as large in diameter as the charging opening in the drum.
12. The combination in a mixing machine, of a rotatable drum, the lower part of which is inclined in one direction longitudinally, and flights arranged in said drum and longitudinally thereof, and inclined on the ascending side of the drum in the opposite direction to which the lower part of the drum is inclined so that material lifted by said flights and retained thereon will tend to move on the flights toward one end of the 100

drum and when discharged from said flights on to the oppositely inclined lower part of the drum, will tend to move toward the other end of the drum, whereby the material within the drum is caused to circulate in a continual cycle from one end of the drum to the other end of the drum and back again.

13. The combination in a mixing machine of a rotatable drum provided with elevating flights on the interior thereof, a chute supported outside of said drum so that the arc of movement of the chute will be concave downward, and means for moving said

chute endwise more or less either into the 15 drum or out of the same, said means being adapted to reverse the inclination of the chute during its endwise movement, and the chute being so mounted as to cause it to be inclined toward the bottom of the drum 20 when occupying the innermost of its two positions.

In witness whereof I hereto affix my signature in presence of two witnesses.
